SHIPPING CASE

Orville A. McRill and Fred M. Lappin,
Wayne City, Ill.

Application October 2, 1934, Serial No. 746,598

4 Claims. (Cl. 217—12)

The present invention relates to new and useful improvements in shipping cases for eggs and fruit, particularly the former, and has for its primary object to provide, in a manner as herein set forth, a case of this character embodying a novel construction, combination and arrangement of parts through the medium of which said case may be expeditiously collapsed or folded in a manner to occupy a minimum of space when being returned or stored.

Another important object of the invention is to provide a collapsible shipping case comprising novel hinge means for connecting certain of the members of said case together.

Still another important object of the invention is to provide a shipping case of the character described which includes novel means for detachably securing the lid in position.

Other objects of the invention are to provide a shipping case of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a plan view of a shipping case constructed in accordance with the present invention, showing the parts thereof extended.

Figure 2 is a perspective view, showing the case partially set up or assembled, the lid being omitted.

Figure 3 is a view in side elevation of the case.

Figure 4 is an end elevational view.

Figure 5 is a detailed view in perspective of one of the bendable securing tongues.

Figure 6 is a detailed view in perspective of one of the hinge loops.

Referring now to the drawings in detail, it will be seen that the embodiment of the present invention which has been illustrated comprises a bottom 1, side walls 2 and 3, end walls 4, a lid 5, and a partition 6. The members 1 to 6 inclusive, are of any suitable material, preferably fiber board.

Hinges designated generally by the reference numeral 7 connect the side walls 2 and 3 to the bottom 1, the end walls 4 to the side wall 2, and the partition 6 to an intermediate portion of the side wall 3, as illustrated to advantage in Figure

1 of the drawings. Each hinge 7 comprises substantially U-shaped, sheet metal loops 8 which are mounted on the adjacent edges of each of the members to be connected together, said loops straddling said members and being rigidly secured thereto by prongs 9 and 10 (see Figure 6). The single prongs 9, on one end of the loops 8, are driven through the member on which said loops are mounted and clinched over the other end of said loop between the prongs 10, and said prongs 10 are, of course, driven in the opposite direction through the member and clinched over said one end of the loop adjacent the opposite sides of the prong 9. A length of wire 11 is then bent or folded upon itself and the legs or folds of said wire are inserted through the loops 8 and twisted together, as at 12. In the hinge structure which connects the partition 6 to the side wall 3, the loops 8 on one side of said hinge structure extend through said side wall 3, as best seen in Figures 1, 2 and 3 of the drawings.

Bendable sheet metal tongues 13 are secured on the lower and one vertical end of the end walls 4 for engagement in the slots 14 of angle irons 15 which are mounted on the ends of the bottom 1 and the side wall 3 for releasably securing said end walls 4 thereto. The tongues 13 include integral prongs 16 on one end which are driven through end walls 4 and clinched, and prongs 17 which are struck from intermediate portions 30 of said tongues and bent over the edges of said end walls. The outer or free ends of the tongues 13 are pointed, as at 18, to facilitate insertion in the slots 15. The tongues 13 are also provided on the lower and one vertical edge of the partition 6 for connection with angle irons 15 on the bottom 1 and the side wall 2.

Mounted on the upper edges of the end walls 4 are metallic cleats which are designated generally by the reference numeral 19. Cleats 19 project outwardly from the end walls 4 in a manner to provide handles for carrying the case. The cleats 19 are formed from a single sheet of metal folded upon itself, the folds being spaced from each other and bent downwardly at right angles in a manner to straddle the end walls 4 to which said folds are rigidly secured by integral prongs 20. The upper portions of the metallic cleats 19 have formed therein slots 21 for the reception of securing tongues 22 which are struck downwardly from metallic strips 23 which are secured to the lower side of the lid 5.

When assembling or setting up the case, the side walls 2 and 3 are swung to a substantially vertical position on the bottom 1 and the partition 55

6 is secured to said bottom 1 and to the side wall 2. The end walls 4 are then secured to the bottom 1 and to the side wall 3. The case is then ready to be filled. After the case has been 5 filled, the tongues 22 on the lid 5 are introduced into the slots 21 in the cleats 19 and said lid 5 is then shifted laterally in a manner to drive the tongues 22 home in said slots 21. In Figure 1 of the drawings, it will be noted that the tongues 22 10 of the right hand ends of the strips 23 project beyond the adjacent longitudinal edge of the lid 5. These right hand tongues 22, after the lid has been shifted laterally as above described, project beyond the corresponding ends of the 15 cleats 19 and are bent upwardly, as seen in Figure 3 of the drawings, for securing the lid in position. Of course, when the case is to be folded the foregoing operation is substantially reversed.

It is believed that the many advantages of a 20 collapsible shipping case constructed in accordance with the present invention will be readily understood, and although a preferred embodiment of the invention is as illustrated and described, it is to be understood that changes in the 25 details of the construction and in the combination and arrangement of parts may be resorted to which will fall within the scope of the invention as claimed.

What is claimed is:

- 30 1. A collapsible shipping case of the class described comprising a bottom, side walls hingedly mounted on the bottom, end walls hingedly mounted on one of the side walls, means for detachably securing said end walls to the bottom 35 and said other side wall, said means including angle irons mounted on the bottom and said other side wall, said angle irons having slots therein, bendable sheet metal tongues mounted on the end walls, said tongues comprising integral 40 prongs on one end of said tongues anchored in the end walls and further comprising prongs struck from intermediate portions of said tongues and engaged over certain of the edges of the end walls, the other ends of the tongues being 45 pointed to facilitate insertion in the slots, a lid,

and means for detachably securing the lid to the end walls.

2. A shipping case comprising a bottom, side walls, end walls and a lid, and means for detachably securing the lid to the end walls, said means including cleats mounted on the end walls, said cleats formed from sheet metal folded upon itself, the folds being spaced from each other and bent at right angles and straddling the end walls, means for securing the cleats to the end 10 walls, one of the folds of the cleats having slots therein, metallic strips mounted on the lid, and bendable tongues on the metallic strips engageable in the slots.

3. A collapsible shipping case of the class described comprising a bottom, side walls and end walls, and means for hingedly connecting the side walls to the bottom and the end walls to one of the side walls, each of said means including substantially U-shaped, sheet metal loops straddling the adjacent marginal portions of the connected members and projecting therefrom, and a length of wire bent upon itself and inserted through the loops and twisted together therebetween.

4. A collapsible shipping case of the class described comprising a bottom, side walls, and end walls, and means for hingedly connecting the side walls to the bottom and the end walls to one of the side walls, each of said means including substantially U-shaped, sheet metal loops straddling the adjacent marginal portions of the connected members and projecting therefrom, and a length of wire bent upon itself and inserted 30 through the loops and twisted together therebetween, said loops including a pair of integral prongs on one end extending through the members and bent over the other ends of said loops and further including an integral prong on said 35 other end extending through the member and bent over said one end between the first named prongs.

ORVILLE A. MCRIIL.
